Theodore W. Dillagore, of Philadelphia, Pa.
Assignee to Savery & Co. at same place.
Letters Patent No. 1189, Dated Jan. 10, 1860.

The schedule referred to in these Letters Patent and making part of the same.

To all whom it may concern:

Be it known that, Theodore W. Dillagore, of the City of Philadelphia, in the State of Pennsylvania, have invented or produced a new and original ornamental Design for "fire dogs," and I do hereby declare that the following is a full, clear and exact description of the same, reference being had to the annexed drawing, making a part of this specification and to the letters of reference marked thereon.

The said design I call "The oak vine pattern," and it consists of a representation of an oak vine twisted together and bearing acorns, supported by an ornamental base - as herein after described, to be cast in metal, and used as the front part of a "fire dog."

In the drawing, A. represents the oak vine, and B. the ornamented base.

The vine (A) is twisted together, bearing acorns c, c, c, c, and rests in an upright position upon the base (B) - as seen in the drawing. The base (B) is bifurcate as usual, the two legs d, d, being ornamented with the scrolls 1. 1. Knees 2. 2, and indentations 3. 3, as shown in the drawing, the feet e, e, being of the ornamental scroll form shown. The body of the base (B) is ornamented with the scrolls 4. 4, surrounding a plain field, 5, suitable for the name of the manufacturer.

The upper part, or neck, of the said base consists of the ornamental curved spouts 6.6.6, united together and terminating in upward turned leaves along the upper edge, as seen in the drawing; The whole being of the configuration shown.

What I claim as my invention and desire to secure by letters Patent is, the herein described configuration and ornamentation, consisting of the oak vine (A) and the base (B), as a new and original ornamental design for "fire dogs".
